(57) **CLAIM**

The ornamental design for an expanded heart-valve stent, as
shown and described.

DESCRIPTION

FIG. 1 is a perspective view of a first embodiment of an
expanded heart-valve stent of the present application;
FIG. 2 is a front elevational view of the first embodiment of
the expanded heart-valve stent;
FIG. 3 is a rear elevational view of the first embodiment of
the expanded heart-valve stent;
FIG. 4 is a top plan view of the first embodiment of the
expanded heart-valve stent;
FIG. 5 is a bottom plan view of the first embodiment of the
expanded heart-valve stent;
FIG. 6 is a left side elevational view of the first embodiment
of the expanded heart-valve stent;
FIG. 7 is a right side elevational view of the first embodiment
of the expanded heart-valve stent;
FIG. 8 is a perspective view of a second embodiment of an
expanded heart-valve stent of the present application;
FIG. 9 is a front elevational view of the second embodiment
of the expanded heart-valve stent;
FIG. 10 is a rear elevational view of the second embodiment
of the expanded heart-valve stent;
FIG. 11 is a top plan view of the second embodiment of the
expanded heart-valve stent;
FIG. 12 is a bottom plan view of the second embodiment of
the expanded heart-valve stent;
FIG. 13 is a left side elevational view of the second
embodiment of the expanded heart-valve stent; and,
FIG. 14 is a right side elevational view of the second
embodiment of the expanded heart-valve stent.
The broken lines are for the purpose of illustrating environment
only and form no part of the claimed design.
